GEAR SHIFTING CONSOLE FOR A BICYCLE

Keizo Shimano, 81 Midorigaoka, Minamichō, 3 cho, Sakai,
and Norio Sato, 414 Takesono-cho, Suita, both of Osaka
Prefecture, Japan

Filed Dec. 6, 1967, Ser. No. 9,663

Claims priority, application Japan Aug. 11, 1967

Term of patent 7 years

(Cl. D90—1)

FIG. 5

FIG. 1

FIG. 3

FIG. 2

FIG. 4

FIG. 1 is a top plan view of a gear shifting console for a bicycle;

FIG. 2 is a back view thereof;

FIG. 3 is a front view thereof;

FIG. 4 is a bottom-plan view thereof;

FIG. 5 is a left side view thereof.

We claim:

The ornamental design for a gear shifting console for a bicycle, substantially as shown.
